[57] CLAIM

The ornamental design for a faucet valve, substantially as shown and described.

DESCRIPTION

FIG. 1 is a perspective view of a faucet valve showing my new design;
 FIG. 2 is a side elevational view thereof, showing the valve in a closed position;
 FIG. 3 is another side elevational view thereof, showing the valve in an open position;
 FIG. 4 is a third side elevational view thereof, showing the valve in another open position;
 FIG. 5 is a front elevational view of FIG. 3, and
 FIG. 6 is a cross sectional view taken on line 6—6 of FIG. 3.
 The broken line representation of a faucet spout and an aerator in FIGS. 1 through 5 and the fragmentary broken line representation of a plate in FIG. 3 are for purposes of illustration only.

FIG. 1

FIG. 2

FIG. 3

FIG. 4

FIG. 5
